UNITED STATES PATENT OFFICE.

ARTHUR J. MOXHAM, OF JOHNSTOWN, PENNSYLVANIA.

PROCESS OF MAKING CENTER-BEARING GIRDER-RAILS.

SPECIFICATION forming part of Letters Patent No. 355,780, dated January 11, 1887.

Application filed September 16, 1886. Serial No. 213,670. (No model.)

To all whom it may concern:

Be it known that I, ARTHUR J. MOXHAM, of Johnstown, in the county of Cambria and State of Pennsylvania, have invented a new and useful Process of Making Center-Bearing Girder Car-Rails, which invention is fully set forth and illustrated in the following specification and accompanying drawings.

The object of this invention is to provide a ready means of manufacturing a girder-rail having a head the under part of which is recessed, as hereinafter described, and for which form of rail I now have an application for a patent pending, said application being filed herewith and numbered 213,673.

The process constituting this invention is hereinafter particularly described, and specifically set forth in the claim.

In the accompanying drawings, Figure 1 shows a portion of a roll-pass containing a rolled blank of metal or primary form. Fig. 2 shows part of a roll-pass in which the blank shown in Fig. 1 is partially bent on either side of its web part. Fig. 3 shows part of a roll-pass in which said blank is further bent to the finished form desired, the head of which product is delivered having interior recesses between it and the web of the rail. Fig. 4 shows part of a pass which is adapted to similarly bend the upper portion or head of a rail-section the lower portion of whose web is provided with a wide flange or foot.

In the several figures of the drawings the metal forming the blank and the bent or partly finished rail, and also the finished rail, is indicated by the letter C, the parts of the respective upper and lower rolls being indicated, respectively, by the letters A and B and the parting-lines of the rolls by the letter X.

In Figs. 1 and 4, although the parting-lines are shown as if the rolls were vertical, it is to be understood that such is not the case, each of the forms therein shown being operated upon edgewise by the rolls, as hereinafter explained.

It will be noted by the dividing-lines of the passes *m* that Figs. 2 and 3 are rolled with the web of the rail vertical. While it would not be impossible to bend the upper portion of

this form of rail into the desired shape of 50 head by rolling the same on its side instead of vertically, it is considered preferable to roll vertically, as shown, as a larger part of the active roll-surface can be brought to bear in effecting the desired bending process.

In Fig. 4 the rail is treated edgewise for the same purpose—namely, to secure the maximum effect during the bending process. By the ordinary method of rolling out recesses in intricate corners or parts of difficult sections 60 such portions are rendered accessible to roll action by so shaping the same in relation to their line of delivery that the revolution of the rolls in a vertical plane does not clamp or bind them, as is done, for instance, in Patent 65 No. 347,283, issued August 10, 1886. Such course results generally in sacrificing the exact shape of section wanted to the contingencies of manufacture.

In the process of manufacturing here shown 70 the form or blank is designed of such shape and proportions as to be feasibly rolled by the ordinary process of rolling in the first case, and by subsequent bending to give the desired finished shape in the second case, it being necessary in the design of the form or blank to take into consideration the change of form 75 that will be effected by the bending and to provide for such change.

It will be noted that the shapes of the passes 80 are such that the process is that purely of bending, not rolling, and the bending is effected without liability to distortion of the metal during the process.

Having thus fully described my said process, as of my invention I claim—

The process of making center-bearing girder car-rails, consisting, first, in forming a T-shaped bar of metal, and then downwardly bending the T-head of said bar, so as to leave a central bearing and two side trams recessed under said central portion, substantially as and for the purposes set forth.

ARTHUR J. MOXHAM.
